UNITED STATES PATENT OFFICE

117,381

DESIGN FOR A GRATER HOLDER

Marguerite Nelson, Kansas City, Mo.

Application March 2, 1939, Serial No. 83,291

Term of patent 3½ years

To all whom it may concern:

Be it known that I, Marguerite Nelson, a citizen of the United States, residing at Kansas City, in the county of Jackson and State of Missouri, have invented a new, original, and ornamental Design for a Grater Holder, of which the following is a specification, reference being had to the accompanying drawing, forming a part thereof.

Fig. 1 is a perspective view of the grater holder, showing my design.

Fig. 2 is a side elevational view thereof; and, Fig. 3 is an end elevational view thereof.

I claim:

The ornamental design for a grater holder, as shown.

MARGUERITE NELSON.
